Inventor

Joseph A. Innerarity

UNITED STATES PATENT OFFICE.

JOSEPH A. INNERARITY, OF SLIDELL, LOUISIANA.

DANGER-INDICATING DEVICE FOR THERMOSTATS.

Application filed March 27, 1925. Serial No. 18,737.

The present invention relates to thermostats for use in connection with the radiators of automobiles for indicating the temperature of the water therein, and aims to provide a novel and improved device of this character which will render a signal when the temperature of the water reaches an abnormal degree.

Another object of the invention is the provision of a thermostat having a pair of electric contacts carried thereby for contacting with the mercury in the thermostat for closing an electric circuit when said mercury rises to a height that bridges the contacts, said contacts having their interior surfaces flush with the mercury opening in the thermostat so as not to interfere with the movement of the mercury.

It is also an object of the invention to provide a danger indicating device for thermostats, which is simple and substantial in construction, which can be manufactured economically, and which will be thoroughly efficient and practical in use.

With the foregoing and other objects in view, which will be apparent as the description proceeds, the invention resides in the construction and arrangement of parts, as hereinafter described and claimed, it being understood that changes can be made within the scope of what is claimed, without departing from the spirit of the invention.

The invention is illustrated in the accompanying drawings, wherein:

Figure 1 is a side elevation of my improved device, showing portions thereof in section,

Figure 2 is a vertical section through the same,

Figure 3 is an enlarged section showing the manner of mounting the electric contacts,

Figure 4 is a section taken on line 4—4 of Figure 3, and

Figure 5 is a detail view showing the type of electric connection used.

Referring to the drawings, the numeral 10 designates a supporting frame or casing having removably attached thereto on one side a front plate 11, while on the opposite side is arranged a glass panel 12, said supporting frame or casing also having a depending screw threaded shank 13 which extends downwardly through a radiator cap 14 and has threaded on the lower end thereof a binding nut 15 in order that the device may

be rigidly carried by the radiator cap. The screw threaded shank 13 is hollow and has arranged therein a mercury bulb 16 having an upwardly extending mercury tube 17, 60 which has the upper extremity thereof received in a socket 18 provided in the upper portion of the supporting frame 10.

The mercury tube 17 has a pair of rectangular openings 19 provided in the side thereof and arranged in spaced relation to each other. Received in the rectangular openings 19 are contact members 20, which are of a size sufficient to completely close said openings, and which have the interior surfaces 70 thereof curved, as at 21, for conforming to the same configuration as the bore of the tube 17, said contacts 20 being provided with reduced neck portions 22 and a threaded shank 23. In order that the contacts 20 75 may be secured in a rigid manner to the mercury tube 17 a mass of sealing material, which may be glass and is indicated by the numeral 24, is placed on the tube adjacent the rectangular openings therein and the 80 contacts 20 in such a manner that portions thereof are received in the reduced necks 22 of the contacts which will form the means that secures said contacts permanently to the mercury tube 17.

Attached to the threaded shanks 23 of the contacts 20 are the ends of a pair of electric wires 25 and 26, which are held in place by nuts 27, or the like. The opposite ends of the wires 25 and 26 extend towards each 90 other and are secured in an electric connection socket 28 arranged in one side of the supporting frame or casing 10. Said socket 28 is secured in position by means of a set screw 29, while a removable connection plug 95 30 extends into the open end thereof and has attached to the same a pair of electric wires 31 and 32. Said wires 31 and 32 extend to a point away from my improved device and have arranged in circuit therewith an electric horn 33 and a battery 34, or any other supply of current.

In operation of the device, the mercury contained in the bulb 16 and tube 17 rises and lowers according to the temperature of the water in the radiator. Should the temperature of the water reach an abnormal degree, the mercury in the tube will rise to a point where the same bridges the contacts 20, thus closing an electric circuit to the horn 33, in order to sound an alarm. It is to be noted that the contacts 20 are spaced from

each other with the uppermost contact positioned at a point only reached by the mercury when the water in the radiator has reached a point where the same will not properly cool the engine, and that the interior surfaces of the contacts are curved to conform to the shape of the bore in the tube 17 in order that the movement of the mercury will not be interfered with.

10 When it is desired to remove the radiator cap 14 for supplying a fresh quantity of water to the radiator, the plug 30 may be readily removed from the socket 28 in order to permit the radiator cap to be turned for 15 removing the same.

Having thus described my invention, what I claim as new is:

In a thermostat, a mercury tube provided at its sides with spaced openings which are

rectangular, contact members having head 20 portions which are rectangular in transverse section and which fit snugly in the openings of the tube, said contact members having reduced neck portions located exteriorly of the tube, sealing material adhering to the 25 exterior surface of the tube and bearing against the outer surfaces of the head portions of the contact members and against the surfaces of the neck portions of the contact members, conductor wires connected with the 30 outer ends of the contact members, and nuts screwed upon the outer ends of the contact members and holding the wires against the outer faces of the heads.

In testimony whereof, I have affixed my 35 signature.

JOSEPH A. INNERARITY.
